FREQUENCY CONTROL FOR RADIO DISTRIBUTING SYSTEMS

Application filed February 9, 1924. Serial No. 691,822.

My invention relates to radio broadcasting systems, and especially to those designed for regional distribution. It has for its object to produce a system which shall meet the following requirements:

- 5 1. All receiving instruments in the system to be standard and fixed in their tuning, so as to operate always on one and the same wave length.
- 10 2. All receiving instruments to be able to receive efficiently, with either telephone headset or loud speaker, all modulations and signals transmitted from all sending stations, regardless of the wave lengths on which they are transmitted.
- 15 3. All receiving instruments to be of very simple character, and so connected to the wired circuits with which they are identified, that they may be supervised, tested, supplied with electric current, and if desired, their service metered, from a central point, over said wired circuits.
- 20 4. All receiving instruments to be available for ordinary telephonic use over the wired circuits, as well as fulfilling the function of radio telephone instruments, so that each radio receiving instrument may be also an extension telephone, if so desired.
- 25 5. All receiving instruments to be so designed that they may be grouped or connected either as many-party-line subscribers on the wired circuits, or each station may have a private wire, all in accordance with standard telephone practice. This also implies the sending and receiving of signals to and from party line stations, and the individual metering of several parties on one line.
- 30 6. The entire system of radio distribution, with all the instruments thereon, to be operable independently of the telephone exchange system, with which it is associated, and whose wired circuits are used in the radio distributing system. This implies further that the two systems may be separated in management, as for example, in time of war or public necessity.
- 35 7. All instruments and their circuits to be so related to a central radio exchange and its operating switchboards, that direct communication may be had both ways, during

broadcasting, that is, by high frequency currents from the central office to the subscribers, and by audio frequency currents from the subscribers to the central office. This implies not only that a subscriber can speak to the central office operator at any time, but also that performers may hear the applause of the listening subscribers.

Other purposes and features of the invention will sufficiently appear from the detailed description hereinafter. Briefly stated, I attain my object and meet the foregoing requirements as follows:

(1) and (2) are met by providing a central office receiving set, to receive modulated waves from distant stations, which I may call primary stations, on various wave lengths, and while faithfully reproducing or relaying the modulations, transforming the frequency of the carrier waves and transmitting a resultant modulated long wave over the subscribers' lines to the radio telephone substations. The long carrier wave used for this final wire line distribution is always the same, regardless of variations in wave lengths of received signals. This means that the central office receiving and relaying apparatus must be not only in effect a frequency transformer, but must also be an adjustable or variable frequency transformer, adapted to take in variable frequency through a wide range on its input side, and to produce always the same wave length on its output side, maintaining the same modulations without loss. In certain prior copending applications I have described one means for doing this which involves however a reduction to audio frequency. In the present case I prefer to use the heterodyne principle, which also enables me to provide a local balancing circuit containing an oscillator and if desired a modulator stage, to maintain continuity of service with the same apparatus for local programs when distant stations are not sending or when it is not desired to receive them. Such a receiving and relaying apparatus, therefore includes as elements (a) a tunable receiving circuit for distant stations including an antenna or its equivalent; (b) a local oscillator circuit tunable

for heterodyning the carrier waves received from the distant stations; (c) a second local oscillator circuit tunable to replace the carrier wave frequencies of distant stations; (d) intermediate frequency filtering and amplifying means tuned to the constant wave length of the desired beat waves which are to be transmitted as carrier current to the subscribers' stations; (e) modulating means for either or both of the local oscillator circuits employed in heterodyning; and (f) means for tuning or adjusting the subscribers' circuits permanently to the fixed wave length to be distributed thereover. For examples, the distant station receiving circuit may be adapted to wave lengths from say 150 to 500 meters; the first local oscillator circuits must then have the same range of frequencies, the first oscillator circuit being tuned in receiving to give a constant difference of say 30,000 cycles per second from the carrier frequency of the distant station being received; and the second oscillator circuit being tunable within the said range to the same frequency or wave length as the last distant station received. The resultant or beat frequency due to any combination thus set up is constant, so that carrier current at a standard wave length of say 10,000 meters is always impressed upon subscribers' lines. Moreover, the intermediate frequency amplifying means is permanently tuned to the long wave or beat frequency, which for reasons well understood in the art can be amplified more efficiently than short waves. By providing modulating means for the first oscillating circuit, local modulations can be impressed on the beat wave or carrier current transmitted to the subscribers, in addition to the modulations of the carrier waves received from a distant station. Thus, local announcers may interpolate features or remarks in a program, or local performers or instruments may cooperate with the performers at the distant station. The arrangement is sufficiently elastic so that a number of performers at different points both within and without the local area, may be associated together, as for example, different sections of an orchestra or different orchestras or bands, or different parts of a chorus. To enable the operator at the local central station, and the local performers if necessary, to listen in on the waves as received and as heterodyned, I provide one or more local receiving circuits preferably connected on the output side of the radio frequency amplifying element in the above combination. This is necessary in any case for the local operator, in order that he may properly tune his circuits. His instrument connected as stated, would be permanently tuned to the long beat, that is to say, 10,000 meters wave length; and hence would serve as a wave meter for the exact adjustment of his local oscillator or heterodyne circuit. The same is true of the subscribers' instruments, all of which are standardized for the fixed wave length of the beat, assumed in this case to be 10,000 meters. As set forth in prior copending applications, and as stated above at (3) the operator has access over subscribers' lines to the subscribers' receiving instruments, for the purpose of supervising, testing, etc. The operator can therefore check his own receiving circuit, and calibrate the entire system so to speak, by first adjusting his oscillator circuits so that his own receiving set is at maximum efficiency, and then listening in on various subscribers' circuits as a further check. This access to the subscribers' instruments, so that the actual performance of the receiving elements in the system may be ascertained from central, I consider very important, as it eliminates all elements of uncertainty and gives the central station exact knowledge and perfect control without disturbing the subscribers and without any necessity for sending out inspectors or maintaining test stations.

(4) and (5). I employ at the subscriber's station as the essential elements a coupler, a rectifier or detector, a telephone receiver, and a telephone transmitter. A telephone condenser of the usual radio type, a tuning condenser if desired, and separate switches for the high frequency receiver and the telephone transmitter may also be employed, as well as a step down transformer so that a low wound telephone receiver may be used, making the instrument for audio purposes an ordinary telephone. If used on a party-line, as an extension phone, it may be desirable also to provide the usual ringer, and if head telephone receivers are to be employed, a crystal detector or the equivalent may be used. Where a loud speaker is desired, a single stage of audio amplification is ordinarily sufficient, and if a dynamic type of loud speaker is employed, current can be taken over the telephone line so that either with or without tubes, the use of local batteries at the subscriber's station can be eliminated. Extreme sensitiveness is not necessary, because while the modulations are the same modulations originally impressed on the short carrier waves sent from the distant station, they are carried to the subscribers on a low frequency carrier current, that is to say, on a long wave length, over the wires, and with substantial reinforced energy imparted to them at the local distributing station. With respect to the party-line feature, it goes without saying that when the high frequency receiving instrument is designed with the necessary elements to make it an extension telephone set, it can be adapted to any use for which an ordinary telephone set is usually employed, including party-line service. The transmission of modulated carrier currents

over a party-line at one or more frequencies and in sufficient volume to supply a plurality of stations thereon offers no difficulties, inasmuch as the lines to the subscribers' stations are in effect extensions of the bus bars or wires at the central station, which must be supplied with sufficient carrier current for all the lines connected to said busbars. Arrangements for this purpose, such as amplifier tubes in parallel, are available in the art, and need not be specifically described.

(6) and (7). As will hereinafter appear, the radio exchange is operated in this system as an entirely separate entity from the telephone exchange to which the subscribers' lines may be connected. It is true that the provision of a separate radio switchboard and operator's station would probably be sufficient in conjunction with a telephone exchange switchboard, for the important objects herein set forth, but as this present system is only part of a complete organization which may be country-wide, and in many districts involve groups of exchange centers, I have chosen to treat the radio telephone system, not as an auxiliary to the telephone system, but as a system complete in itself, of equal importance with the telephone system, but having very different functions. The purpose of the telephone exchange system is to enable individual subscribers to communicate with each other. It affords no means of simultaneous communication with all of its subscribers, or from all of its subscribers to any given point, or of simultaneous communication with any more subscribers than can be reached at one time through the percentage of connecting devices provided on the telephone switchboards. The radio exchange system, on the other hand, is not adapted nor intended to interconnect individual subscribers, but is preferably adapted to handling subscribers in masses or groups, from which individuals may be selected by voluntary action. With the apparatus hereinbefore mentioned at a subscriber's station, he may be called individually and communicated with in the ordinary way over his telephone circuit, by the radio operator, or he may be called by name during the broadcasting, and may respond over his telephone circuit, using his radio instrument as a telephone for the purpose, or he may be called either by wire or my name, and connected to the broadcasting circuit at central so that he in turn may communicate by broadcast with all the other subscribers. Various other combinations can be made, sufficient to make the radio exchange system as such very valuable as a separate means of communication in time of war or public emergency.

My invention is illustrated in the accompanying drawings in which:

65 Fig. 1 is a diagram of receiving and trans-

mitting apparatus at the radio central office or exchange.

Fig. 2 is a similar diagram showing the extension by way of wired circuits to a subscriber's station and also indicating duplication of the apparatus of Fig. 1, in order that different classes of service or programs may be simultaneously given.

Fig. 3 is a diagram of an oscillator circuit with modulator adapted to connect to the coupler in Fig. 1.

Fig. 4 is a diagram showing a subscriber's receiving instrument provided with a telephone transmitter, and connections such as an extension telephone.

Fig. 5 is a similar diagram showing a further modification of the subscriber's station circuits in which a crystal detector is employed for simplicity, in parallel with the high frequency telephone receiver.

Fig. 6 is a further diagram of another modification employing the same elements as Fig. 5, but with the crystal detector in series with the telephone receiver, and the latter shunted by a by-pass condenser.

Fig. 7 is a diagram of a still further modification in which a vacuum tube detector is employed, with its filament supplied with energizing current over the telephone line from central, and its plate circuit connected across the subscriber's telephone branch, which may be supplied with a special form of telephone receiver, or with the ordinary telephone set, upon which the subscriber may then receive all messages, both telephonic and radio.

Fig. 8 is a diagram showing a tuned coupler spanning the gap between the radio exchange terminals and the telephone exchange terminals of a line.

Referring to the drawings, R indicates in general a radio central office or exchange through which modulated waves received from a distance are relayed, and from which local originating signals and programs may be transmitted to subscribers in a local area or region immediately surrounding said central office. Transmission to the subscriber's station is illustrated in Fig. 2 as by means of wired circuits over which modulated waves from central are guided. These circuits afford access to the receiving radio telephone stations by central office operators and wire chief for testing purposes, and for supervision and control. They also serve to carry energizing current, as for example battery current or low frequency alternating current, to the subscriber's station for use in connection with vacuum tubes and loud speakers, if the same are employed. A third service which may also be imposed upon the wires is that of metering the use of the radio receiving stations in substantial accordance with telephone exchange practice. It is not the purpose of the present application to develop detailed connections and characteristics of the line

circuits or the subscriber's receiving apparatus; but rather to set forth the combinations of central office and subscriber's apparatus necessary to realize the objects hereinbefore stated. The first of these is to produce frequency transformation at the central station, so that any distant station may be received as at present, on its own wave length and the modulations thereof may be preserved but transmitted at a different wave length to the local subscribers, said wave length being that to which their instruments are standardized and permanently tuned. This arrangement lends itself with particular readiness to wired circuits, or line radio transmission to the subscribers, because if incoming waves are transformed in frequency to much longer waves, as for example, waves of 10,000 meters in length, not only are these long waves more suitable for transmission over the subscribers' wired circuits, but they are also susceptible of amplification at the central station and if desired at the subscribers' stations, with higher efficiency than shorter waves. The frequency suggested, viz; 30,000 cycles per second, approaches audio frequency so nearly, that transformers may be employed with iron cores, thereby rendering it possible to employ said transformers through a range of frequencies extending into the audio.

While in copending applications I have described other means of changing the frequency of the carrier wave in relaying from distant stations to subscribers, in the present case I show for this purpose a superheterodyne circuit, employing two local oscillator circuits, either or both of which may be equipped with modulators. In Figs. 1 and 3 both of said oscillator circuits are shown thus equipped. In Fig. 1, 1 is the station antenna, 2 is the coupler, and 3 is the ground connection, all of usual or any desired construction suitable for the purpose. For a purpose presently to be explained, I include switch contacts 4 and 5 in the antenna and ground connections and another switch contact 6 which when closed, shunts a load coil in the local receiving circuit. The coupler 2 in the present case has three windings, 2^a, 2^b, and 2^c. The first of these is the antenna coil. The second is the secondary coil in the receiving circuit, and the third, 2^c, is a coupler for the oscillator circuit of Fig. 3. From the coil 2^b wires 7 and 8 extend respectively to the grid and filament terminals of the first tube 9, which is a detector tube. It may be stated here that the specific circuit I have chosen for illustration employs two detector tubes, one for heterodyning, and the second at the subscriber's station. The wire connection 7 to the grid 9^a, has interposed in it the usual grid condenser 10 and grid leak 11. The wire 12 from the plate 9^b extends to the primary winding of a radio frequency coupler 13, both windings of which are shunted by by-pass condensers

of suitable capacity. The return from the opposite end of the primary winding of such coupler 13 is by way of wires 14, 15 and 16 to the filament 9^c. Across the wires 7 and 8 a tuning condenser 17 is connected, and the leads 18-19 from the secondary winding of the coupler 13 pass to the first tube 20 of the radio frequency amplifying tubes 20-21 and 22, constituting the usual three stage radio amplifying unit, with coupling transformers 23 and 24 between the tubes. On the output side of this amplifying unit wires 25 and 26 are connected to one winding of a coupler or transformer 27, the other winding of which is connected through suitable condensers to subscribers' line wires, or to the bus bars on which said line wires are grouped according to their classification and method of feed.

The foregoing represents a method of receiving and amplifying modulated waves and putting the same on subscribers' line wires, as generally set forth in my prior copending applications Serial No. 597,422, filed October 27, 1922, Patent No. 1,576,308, granted March 9, 1926, and Serial No. 681,992, filed December 21, 1923, the principal difference up to this point being the use of the detector tube 9. In order to transform the wave length of the carrier current amplified and transmitted over the subscribers' lines I employ a local oscillator circuit designated as a whole by OC. This may be of any desired and suitable construction and arrangement, with or without modulation, but is shown as of a known type with modulation according to the Heising method. The choke coil in the battery circuit required by the Heising method is shown at 28 in the upper right hand portion of Fig. 1, the batteries being shown at that point for convenience. The oscillator circuit OC includes a tube 29, with the usual plate and grid coils 30 and 31, inductively related to each other, and both inductively related to a series coil 32 in the input side 7-8 of the main receiving circuit. The usual by-pass condenser is inserted across the plate-grid circuits, and a tuning condenser 34 is inserted in the wire 35 which at one end is connected to the outer terminal 36 of the coil 31 and the grid and on the other end is connected to a switch arm 37 which may be shifted to one or the other of the points SW and LW, the former being connected by wire 38 to the outer side of the coil 31 and also through the condenser 33 and coil 30 to the plate; while the point LW is connected direct through wire 39 to the circuit of the plate of the oscillator 29. When the switch is on the point SW therefore the condenser 34 is across the terminals of the coil 31 and when the switch is on the point LW it is across the plate and grid terminals. The modulator circuit MC includes a tube 40 and a modulating transmitter and transformer 41 and 42 connected

130

by wires 43 and 44 across the coils 30 and 31. Battery supply for the filaments and plates is taken through wires 16—16^a, and the wires 14—14^a and 15—15^a. It is thought detailed description of these connections is unnecessary. In order to disconnect the modulator circuit MC when desired the switch contacts 45 and 46 are provided in the wires 43 and 44.

With the oscillator circuit OC incoming waves in the antenna circuit 1—2—3 may be heterodyned through the tube 9 so that the modulated carrier wave at beat frequency, which for present purposes has been assumed as a constant at 30,000 cycles per second, will be propagated through the coupler 13 into the amplifier circuits, and after amplification by the tubes 20—21—22 will be imposed upon the subscribers' lines typified at 50—51 in Fig. 1 or the bus wires 50^a, 51^a leading to the busses 52—53, from which connection can be made to any subscriber's line 50^b—51^b, as shown in Fig. 2. The connecting means between the busses and the subscribers' lines are shown as jacks and plugs 54—55—56, but it is to be understood that I do not limit myself in this respect and that this connection may be by any desired means, including a gap spanned by the amplified radio waves, as indicated in Fig. 8 of the drawings, the use of such a tuned gap doing away with the necessity for physical connection between the radio exchange terminals and the telephone exchange terminals of the lines.

Referring to Fig. 8, I have therein shown the bus wires 50^a and 51^a connected to a loop 54^a, taking the place of the terminal jack 54 in Fig. 2. An extension loop 55^a may then be connected to each of the line extensions 50^c—50^d corresponding to the line extensions 50^e and 50^f in Fig. 2. The loops 54^a—56^a are shown as tuned by means of condensers as usual. The subscriber's receiver Sr and his telephone St may be the same as in Fig. 2. In practice, there will also be means indicated by switch contacts as 57 and 58 to break or interchange the connection between any particular heterodyning set such as shown in Fig. 1, and any particular group of lines or the bus therefor as typified in Fig. 2. Further reference will be made to this hereinafter.

Referring to Fig. 3, I have therein shown a second oscillator circuit OC' containing the same elements as the first oscillator OC, but without the short and long wave switch 37 which however may be supplied if the second oscillator is to cover the same range of frequencies as the first oscillator. This second oscillator is connected to the main receiving circuit by wires 47—48 extending to a coupler coil 2^e inductively related to the primary and secondary of the main coupler 2. This connection may be otherwise arranged, so long as the function of the second

oscillator is preserved, which is to replace the distant source of waves forming one component which by composition with the other component due to the oscillator OC produces the beat waves hereinbefore described. When any distant station has ceased transmitting, or when it is desired to substitute local matter for a part of the distant program, the operator opens the antenna switches 4—5 and closes the switches 4^a—5^a in the leads 47—48 to the balancing oscillator OC', which obviously should be previously tuned in any desired or well known manner to the same frequency as the distant station which it replaces.

Referring to Fig. 2, the wires 50^a and 51^a are connected to the output side of the heterodyne circuits in Fig. 1, and supply the bus wires 52—53, to which they are connected, as by jacks and plugs, subscriber's line wires typified by 50^b and 51^b, leading to a subscriber's station SS. At this station St indicates the subscriber's telephone and Sr the subscriber's radiophone receiver. The telephone shown is of the Western Electric standard common battery type; and the radiotelephone includes a telephone receiver 57, shown as a head set, a crystal detector 58, a condenser 59, and a switch 60, which may be operated by a receiver hook lever 60^b. This set is connected by a coupler 61 to the wires 50^b and 51^b with an interposed tuning condenser 62 and cut-off switch contacts 63 and 64, by means of which it may be disconnected from line at will. By making these switches in the form of a double pole double throw unit, the receiving set may conveniently be connected to an antenna and ground when cut off from the line. This connection may also be effected by the telephone switch hook 65 in the telephone set St, after the manner of hook 60^b; so that if desired the radiotelephone set may be operated independently when the telephone is in use for conversation over the line.

I have shown line extensions 50^c and 50^d extending to a pair of jacks 56^a and 56^b, representing multiple terminals of the telephone line on the telephone switchboard at the telephone central exchange. It is to be understood that all desirable and necessary battery supply connections, relays, signals, and associated devices are implied without specific illustration.

The left hand side of Fig. 2 is supposed to represent a part of the radio telephone central exchange containing the apparatus of Fig. 1. The outside lines to the subscribers' stations are supposed to be included between the dotted lines 66 and 67, and the right hand side to show the subscriber's station SS, only. At the station R, the apparatus of Fig. 1 may be duplicated as indicated at 68 and 69 in Fig. 2, supplying bus wires 52^a—53^a, 52^b—53^b, etc. These duplicate het-

- erodyning sets meet several requirements. Each may be tuned to receive from a distant station, or to send out its own waves, on a wave length different from the others, provided the heterodyne circuit is adjusted so as to deliver to the subscribers currents having the standard wave length. Again, they may be tuned in pairs so that when one apparatus is relaying from a distant station, the second one is ready to replace it, with its oscillator circuit OC' (Fig. 3) tuned to correspond to the distant station which it will replace. Again, for preventing reception of the signals by those who are not subscribers, the latter may be grouped on the bus wires 52^a—53^a, etc., and the subscribers may also be classified according to the programs they wish to receive. Each of the apparatuses typified in Fig. 1 and at 68 and 69 in Fig. 2 may deliver a different program, and if the demand exists there may be a sufficient number of these relay sets to enable the subscribers to receive at will from any of the principal broadcasting stations. The selective interconnection of the lines with the busses 52—53, etc., as indicated in Fig. 2 by plugs and jacks may be either automatic or manual, and may be variable or fixed for a time.
- 30 The subscribers' circuits typified as St in Fig. 2 may be varied in various ways and in particular by including a telephone transmitter and otherwise arranging the connections so as to make the set in effect an extension telephone, as indicated in Fig. 4. In this figure the line wires 50^a—51^b are connected to one side of a coupling coil 61 through a tuning condenser and in parallel therewith through the wires 50^a—51^b to the subscriber's ordinary telephone as shown in Fig. 2. The other or local side of the line coupler 61 goes to a high frequency receiving set symbolized by the rectangle RS, the output terminals of this set being connected through a transformer 61^a to the loud speaker 57^c. The usual filament and plate batteries A' and B' are shown, the former controlled by a blade s of a switch S. A second blade s' controls the connection of the induction coil I which when connected forms with the transmitter T and the loud speaker 57^a a standard Western Electric extension telephone set. This set may be used coincidentally with receiving high frequency waves over the line on a set RS, a separate telephone receiver being provided, if desired. The circuit of this extension phone is the same as the circuit shown at subscriber's telephone station St in Fig. 2. The transformer 61^a or its equivalent in other circuits such as Fig. 7, may be a step-down transformer so that the output will be at ordinary telephone voltage, and an ordinary low wound commercial telephone receiver may be employed.
- 65 In such case an ordinary subscriber's tele-

phone may be used for receiving as indicated in Fig. 7. The receiving set RS in this case would employ one or more vacuum tubes, and the telephone receiver, energized through a step down transformer would act as a loud speaker.

Figs. 5, 6, and 7 show other possible variations of the subscriber's circuit. In all of these forms I have shown the coupler 61 or 61^a with an iron core, because the frequency is just above the limit of audibility, and these transformers can therefore be used for repeating back audio frequencies into the telephone line from the subscriber's receiving set RS circuit. In Fig. 7 a tube detector is shown which takes its battery supply for both plate and filament from the telephone line, and in this case the plate circuit would repeat into said line, beside effecting regeneration through the coupler 61. I have indicated a telephone head set bridged across the wires 50^a and 51^b; and it is to be understood that underlying the design in all of these figures is the idea of the central office operator listening in to the actual reception at the subscriber's station.

I claim:

1. In a radio telephone system of broadcast distribution, a central station and a plurality of subscribers' stations interconnected by individual line wires, a source of modulated high frequency radio waves at the central station, an oscillator also at the central station tuned with relation to said high frequency modulated waves so as to produce a relatively low frequency beat wave, above the limit of audition, means to transmit said beat waves carrying the original modulations, over individual line wires to the subscribers' stations, and means at each subscriber's station controlled entirely by the subscriber for detecting said waves and rendering the modulations thereon audible to the subscriber.

2. In a radio telephone system of broadcast distribution, a central station and a plurality of subscribers' stations, with individual line wires interconnecting them, means at the central station for receiving modulated high frequency waves, means also at the central station for generating high frequency waves adapted when combined with the first mentioned waves to produce a relatively low frequency beat carrying the original modulations, means for communicating said modulated beat frequency interchangeably to the subscribers' individual lines, and means in each line for detecting the same and rendering the modulations audible to the subscriber.

3. In a radio telephone system of broadcast distribution, a central station and a plurality of subscribers' stations with individual line wires interconnecting them, a common heterodyne receiving and transmitting apparatus at the central station having input

- terminals adapted to receive modulated waves from distant stations and output terminals adapted to deliver the modulated beat wave due to heterodyning said input waves, means 5 for connecting said output terminals interchangeable or in common to the subscribers' individual lines, and individual means at the subscribers' stations for detecting the heterodyned waves and rendering the modulations thereon audible to the subscriber.
- 10 4. In a radio telephone system of broadcast distribution, a central station and a plurality of subscribers' stations and tuned line wired circuits interconnecting them, means at the central station for heterodyning into the subscribers' lines so as to transform modulated high frequency waves of varying and indeterminate frequencies into modulated low frequency or long waves of standard or fixed 15 frequency therein, and means at the subscriber's station for detecting and rectifying said low frequency waves and rendering the modulations thereon audible to the subscriber.
- 20 5. In a radio telephone system of broadcast distribution, a central station and a plurality of subscribers' stations, a plurality of lines interconnecting them, subscribers' receiving apparatus and lines tuned to a constant 25 frequency, means at the central station to heterodyne modulated high frequency waves of varying frequency and propagate the resultant beat waves at a constant frequency into the subscribers' lines so as to produce therein relatively modulated waves of 30 the fixed frequency to which the lines and subscribers' stations are tuned.
- 35 6. In a radio telephone system of broadcast distribution, a central station and a plurality of subscribers' stations and line wires 40 interconnecting them, receiving apparatus at the subscribers' stations tuned with the lines for efficient reëception at a constant frequency, means for heterodyning high frequency modulated waves of varying frequency to produce correspondingly modulated beat waves of said constant frequency in the subscribers' lines, and means to vary the frequency of one of the heterodyning high 45 frequency waves to maintain the beat constant in the subscribers' lines.
- 50 7. In a system of radio broadcast distribution, a central station and subscribers' stations with subscribers' lines connecting the subscribers' stations with the central station, a radio receiving apparatus at the central station having its input circuit tunable to receive at various frequencies, a local oscillator associated with said receiving set, tunable to produce waves at a suitable frequency to heterodyne with the incoming waves in said input circuit, a second local oscillator also associated with said receiving set and tunable to furnish the input circuit thereof with waves 55 of various frequencies through the same range as those of the waves received from external sources, a tuned circuit adapted to receive the beat waves due to said heterodyning, whether between the first local oscillator and the distant station, or between the two local oscillators, amplifying means connecting said tuned circuits with a subscriber's line and means to impress modulations upon the waves supplied to the input circuit by one of said oscillators.
- 60 8. The system described in claim 7, having means to impress modulations on the waves in either local oscillator circuit at will.
- 65 9. The system described in claim 7 having means to impress modulations on the waves in both of the local oscillator circuits simultaneously.
- 70 10. The system described in claim 7, with means simultaneously controllable, to combine modulated waves received on the input circuit from the external source, and modulated waves received from a local oscillator, so as to produce in the tuned intermediate frequency circuit, a single beat wave carrier having both sets of modulations impressed 75 thereon.
- 75 11. In a system of radio broadcast distribution having a heterodyne receiving set, without a second detector or audio amplifier, means for supplying modulated waves from external sources to the input circuit of said heterodyne receiving set, means for separately supplying modulated waves at suitable heterodyning frequency to said input circuit, a common tuned output circuit therefor 80 adapted to receive and transmit a single superaudio wave train of beat frequency carrying all the initial modulations, means connected with said circuit for amplifying said modulated carrier wave, at said beat frequency, and output terminals for said amplifying means, together with distributive wire circuits tuned to said beat frequency whereby the modulated and amplified single 85 wave train may be transmitted to the ultimate receiving stations.
- 90 12. A receiving and relaying apparatus for systems of radio broadcast distribution, including as elements a tunable receiving circuit for outside stations such as an antenna or its equivalent, a local oscillator circuit tunable for heterodyning with the carrier waves received from the said outside station or stations to produce a resultant beat wave; and a second local oscillator circuit tunable to replace the carrier wave frequencies of the external or distant station.
- 95 13. A system of radio broadcast distribution including the apparatus described in claim 12 with the additional elements of subscribers' receiving circuits permanently tuned to the fixed wave length to be distributed thereover, and means for maintaining the said intermediate frequency or beat wave produced by heterodyning.

14. A system of radio broadcast distribution including the elements described in claim 12, and in addition thereto, intermediate frequency filtering and amplifying means tuned to the constant wave length of the desired beat waves which are to be transmitted as modulated carriers from the relaying apparatus.
15. A system of radio broadcast distribution including elements described in claim 12 and in addition thereto the following: a plurality of subscribers' stations adapted to receive modulated waves distributed from said common receiving and relaying apparatus, means for tuning or adjusting the subscribers' circuits permanently to a fixed wave length, an intermediate frequency filter and amplifying means in said relay apparatus, whereby the output of the same will be maintained in constant tune at the fixed wave length to which the subscribers' receivers are adjusted.
16. The receiving and relaying apparatus described in claim 12 with the addition of modulating means for one of the local oscillator circuits employed in heterodyning to affect modulation of the resultant beat wave.
17. In a system of radio broadcast distribution, the apparatus described in claim 12 arranged so as to produce an intermediate frequency or beat wave, a circuit for said long or intermediate wave permanently tuned to the frequency thereof and subscribers' circuits connected to said tuned circuit together with means at the subscriber's station for demodulating the waves received.
18. In a system of radio broadcast distribution, a central station and subscribers' stations, a receiving and relaying apparatus at said central station adapted to receive at divers frequencies from distant stations, and to transmit to the subscribers in its local area at a fixed standard wave frequency, an operator's demodulating and sound reproducing device adapted to be connected to the output circuit of said relaying apparatus, and means whereby the operator may listen in on the subscribers' circuits, whereby said operator can first check his own receiving circuit and calibrate the entire system by adjusting his oscillator circuits so that his own receiving set operates at maximum efficiency, and then further check the correctness of the tuning by listening in on one or more subscribers' circuits.
19. In a system of radio broadcast distribution, a central station equipped with radio receiving means having an output circuit terminating in a common radiator, a plurality of subscribers' wired circuits extending from said central station to subscribers' stations, and a tuned receiving antenna at the central station for each of said subscribers' lines, whereby modulated high frequency wave trains may be distributed over the subscribers' lines by radiation without physical connection therewith at the central station.
20. In a system of broadcast distribution, a central station and subscribers' stations with wired circuits extending between them, means at the central station for producing modulated high frequency wave trains suitable for transmission over the subscribers' lines, and a common radiator also at the central station for propagating said modulated wave trains in the subscribers' lines by radiation thereto.
21. In a system of broadcast distribution, a subscriber's station having a telephone line and a telephone set, together with a high frequency receiving set connected to said telephone line, having a telephone transmitter and circuit connected the same as the telephone set, but with a step down transformer connected to the output terminals of the high frequency receiver, and a low resistance telephone receiver connected on the low side of said transformer, said telephone receiver being connected with its transmitter so as to be useful as an extension telephone set over the telephone line and also as a loud speaker or receiver for the radio set.
22. In a system of broadcast distribution, a central office and subscribers' stations with wired lines interconnecting them, means at the central station for distributing high frequency modulated wave trains to the subscribers over their line circuits, a telephone set at a subscriber's station, adapted for telephonic use only over his line circuit, and a combined telephone and high frequency receiving set connected in parallel to the line, and provided with means whereby the same telephone receiver may be used to reproduce the modulations received through the high frequency receiver, and to reproduce speech received over the telephone lines direct.
23. In a system of broadcast distribution, a central station, a plurality of subscribers' stations and wired line circuits interconnecting them, together with a telephone at each subscriber's station, means at the central station for interconnecting the lines for telephonic conversation thereover, and a combined telephone talking set and high frequency receiver, connected as an extension telephone across the telephone line at a subscriber's station, together with means at the central station to distribute modulated high frequency wave trains over such subscribers' lines as are provided with such extension receiving instruments.
24. In a system of radio broadcast distribution, a central station and plurality of subscribers' stations, with line circuits interconnecting them, high frequency receiving means at the subscribers' stations, and duplicate heterodyning receiving sets at the central station, each tuned to receive from a distant station, on a wave length different

from the others, but adjusted to deliver to the subscribers currents having a standard wave length.

25. In a system of radio broadcast distribution, a central station, a plurality of subscribers' stations interconnecting them, high frequency receiving means at the subscribers' stations, and heterodyning receiving sets at the central station tuned in pairs and connected so that when one apparatus is re-laying to the subscribers from a distant station, the second one is ready to replace it, with its oscillating circuit tuned to correspond to the station which it may replace.

15 26. In a system of radio broadcast distribution, a central station and a plurality of subscribers' stations connected therewith by tuned circuits provided with superaudio receiving apparatus tuned to a common standard frequency, a heterodyne receiving instrument at the central station, with a filter coupler and amplifying means for an intermediate or long beat wave carrier, means to receive modulated short waves at any frequency, whether from distant stations or local oscillators, and means to distribute said long wave carrier to said tuned subscribers' lines.

In testimony whereof I hereunto affix my
30 signature.

EDWARD E. CLEMENT.
